UNITED STATES PATENT OFFICE.

MILTON L. CROSS, OF PHILADELPHIA, PENNSYLVANIA.

DESIGN FOR A CORNER-BRACKET FOR BEDSTEADS.

SPECIFICATION forming part of Design No. 30,189, dated February 14, 1899.

Application filed January 3, 1899. Serial No. 701,044. Term of patent 7 years.

To all whom it may concern:

Be it known that I, MILTON L. CROSS, a citizen of the United States, and a resident of the city of Philadelphia, State of Pennsylvania, have invented and produced a new and original Design for a Corner-Bracket for Bedsteads, of which the following is a specification, reference being had to the accompanying drawings, forming part of the invention.

- 10 My invention relates to a design for a corner-bracket for bedsteads adapted for use in securing the corner-posts and side rails of a bedstead together and is of the contour shown in the accompanying drawings, in which—
15 Figure 1 is a view illustrating my design in perspective, and Fig. 2 is a front elevation of the same.
The leading feature of my design consists of the vertically-disposed bar A, substantially 20 rectangular, having its outer face B concaved along its entire length, as clearly illustrated

in the drawings. In the concave portion B is an opening extending transversely through the bar A of substantially the shape of an inverted keyhole, having the lower enlarged portion a and terminating in the upper elongated portion b.

The bracket C extends from the rear wall of the bar A for supporting the side rails of the bedstead.

Having thus described my invention, what I claim, and desire to secure by Letters Patent, is—

The design for a corner-bracket for bedsteads substantially as herein shown and described.

In witness whereof I have hereunto set my hand this 28th day of December, A. D. 1898.

MILTON L. CROSS.

Witnesses:

SAMUEL L. HAINES,
J. R. BUNTING.
